UNITED STATES PATENT OFFICE.

ALBERT A. MAINO AND ALBERT NORLANDER, OF NEW BEDFORD, MASSACHUSETTS.

SLUB CATCHER.

Application filed June 19, 1928. Serial No. 286,563.

Our invention relates to thread guides for spoolers and particularly to an adjustable catching device for the arresting of those bunches or imperfections in the thread usually termed slubs. Such defects in the yarn give difficulties in later textile processes and cause delays in operation and waste of time of expensive hands, so that the detection and elimination of these slubs is of very considerable importance.

Devices of this sort have been proposed but they have for the most part had a tendency to scrape the yarn or destroy its finish. Our invention allows an absolute free running of the yarn as long as it is free from defects, but instantly and firmly catches the yarn where any bunch or imperfection exists.

As illustrative of our invention we show in the accompanying drawings an embodiment which is simple and inexpensive, but extremely efficient in operation. The guide proper is of generally standard type and our invention is capable of embodiment in almost any type of guide either as a part of the guide itself or as an attachment thereto.

Throughout the specification and drawings like reference characters are used to indicate corresponding parts, and in the drawings:

Fig. 1 is an elevation of such a device in accordance with our invention.

Fig. 2 a view on the opposite side.

Fig. 3 an end view.

Fig. 4 an enlarged section, and

Fig. 5 a detail showing the edge of the slub catching blade.

We have indicated at 1 a rail clamp on which is formed a thread bar 2 having a broad milled thread running surface 2¹, constituting a run-way for the thread and over which the thread may run freely under normal circumstances. Pivoted above the clamp 1 as at 3 is a rocker arm 4 carrying a pin 5 disposed parallel to the surface 2¹. Pivoted on the pin 5 is a catcher blade 6 which is of slightly greater breadth than the distance between the pin 5 and the surface 2¹ so that the blade if pressed down makes definite contact with the surface 2¹. The edge of the blade 6¹ is beveled so that in its normal position of slight elevation the edge 6¹ is parallel to the surface 2¹.

The blade 6 is provided with a lateral counterweight 7 which normally tends to raise the edge 6¹ of the blade 6 from the surface 2¹. This tendency is controlled by a set screw 8 which contacts with a shoulder 9 so that the device can be accurately set for any size of yarn to be spooled. The thread T running in the direction indicated by the arrow normally passes under the edge 6¹ as it traverses the surface 2¹, but should any bunch or knot or imperfection in the thread reach the edge 6¹, it catches sufficiently to pull the edge 6¹ down on the surface 2¹ thereby arresting the imperfection.

The operation is very simple but very positive and the device responds instantly to any slub above the given size for which the catcher is set. Our device may be designed for any desired type of mounting and its proportions and balance of counterweight produced to meet any desired conditions or type of yarn. With suitable adjustment the catcher has no effect on the normal run of the yarn whatsoever as it passes freely over the smooth broad surface 2¹ and under the edge 6¹ of the blade. When actuated, however, as above described, the edge 6¹ is by the downward swing of the blade brought into direct contact with the surface 2¹ so as to firmly pinch the yarn and to do so the more tightly as the tension is increased.

Various modifications as above suggested may be made, all without departing from the spirit of our invention if within the limits of the appended claims.

What we therefore claim and desire to secure by Letters Patent is:

1. In a device of the class described, a rail clamp presenting a horizontally extending thread run way, a blade pivot extending from said clamp over said run way and spaced therefrom, a blade hung from said pivot with its lower edge disposed substantially to contact said way by movement in the direction of run of the thread, and a counterweight laterally offset from the upper end of said blade and disposed substantially in the plane of the pivot.

2. In a device of the class described, a rail clamp presenting a horizontally extending thread run way, a blade pivot extending from

said clamp substantially directly over said run way and spaced therefrom, a blade hung from said pivot with its lower edge disposed substantially coextensive with said way for 5 contact therewith by movement in the direction of run of the thread, and a counter-weight laterally offset from the upper end of said blade and disposed coextensive with and substantially in the plane of the pivot. In testimony whereof we affix our signatures. 10

ALBERT A. MAINO.
ALBERT NORLANDER.
